(57) **CLAIM**

I claim the ornamental design for a DC fast charger, as shown and described.

DESCRIPTION

FIG. 1 is a front elevation view of a DC fast charger showing the new design.

FIG. 2 is a left side elevation view of the DC fast charger of FIG. 1.

FIG. 3 is a rear elevation view of the DC fast charger of FIG. 1.

FIG. 4 is a right side elevation view of the DC fast charger of FIG. 1.

FIG. 5 is a top plan view of the DC fast charger of FIG. 1.

FIG. 6 is a left perspective view of the DC fast charger of FIG. 1; and,

FIG. 7 is a right perspective view of the DC fast charger of FIG. 1.

The broken lines in the drawings depict portions of the DC fast charger that form no part of the claimed design.

1 Claim, 7 Drawing Sheets
